UNITED STATES PATENT OFFICE.

ALFRED L. WILKES, OF LOS ANGELES, CALIFORNIA.

ELECTRIC-FURNACE CONTROL.

1,377,951.

Specification of Letters Patent. Patented May 10, 1921.

Application filed June 17, 1919. Serial No. 304,852.

To all whom it may concern:

Be it known that I, ALFRED L. WILKES, a citizen of the United States, residing at Los Angeles, in the county of Los Angeles, State of California, have invented new and useful Improvements in Electric-Furnace Controls, of which the following is a specification.

The present invention relates to a control system for electric ovens and it is an object of the invention to provide a control system that will be simple, accurate and reliable.

The invention has to do with apparatus of the general character set forth in my copending application entitled Heat control for electric furnace, filed August 2, 1919, Serial No. 314,858, and is particularly directed to provide a control for electric dental ovens although it may be applied to any electric oven of the same general character. For the purpose of clearly dividing the subject matter of this application and that of said copending application this application has been directed to time control for the heating means of the oven while said copending application has been directed to temperature control. In dental ovens the electricity is not fully turned on and the oven allowed to heat up immediately but the heat must be controlled in such a manner as to cause the oven to heat gradually and remain at certain temperatures for definite periods of time. When the oven has reached a maximum temperature it is necessary that it should be turned off and allowed to cool. This heat control is necessary in dental ovens in order to properly bake the porcelain used in dental work.

Heretofore electric dental ovens have been provided with resistance controlled by hand to control the heat of the oven and the temperature during the process has been shown by pyrometers. With this arrangement it is necessary to carefully watch the pyrometer in order to keep the oven at the proper temperature and the time must be watched throughout the process in order to obtain the desired results. The process of baking porcelain in such an oven becomes expensive due to the fact that an operator is necessary for the oven throughout the process which extends over considerable length of time. As well as being expensive this process is more or less inaccurate as it is dependent upon the attention and accuracy of the operator.

I have by my invention provided a mecha-

nism that will automatically regulate the heat of the oven throughout the process and turn the oven off when the process is completed. A feature of the invention is that it is entirely automatic and requires no attention after it has been started. The mechanism may be set so as to regulate the heat in the oven in any desired manner and it may be set so as to turn the oven off when it reaches any desired temperature.

Many features of the invention as well as its preferred construction will be clearly understood from the following detailed description of a typical form of the invention throughout which reference is had to the accompanying drawings, in which—

Figure 1 is a plan view of the oven; Fig. 2 is an enlarged detailed section of the main switch taken as indicated by line 2—2 on Fig. 1; Fig. 3 is an enlarged detailed section taken as indicated by line 3—3 on Fig. 1; Fig. 4 is an enlarged plan view of the parts shown in Fig. 3; Fig. 5 is an end view of the oven taken as indicated by line 5—5 on Fig. 1; Fig. 6 is a wiring diagram showing the electrical system; Fig. 7 is a diagram of a modified wiring system; Fig. 8 is a plan view of a modified form of construction; Fig. 9 is an enlarged detail view showing the detailed construction of the modified form of the dial; Fig. 10 is an enlarged detailed view of a portion of the pyrometer; Fig. 11 shows a simplified form of the invention; and Fig. 12 is an enlarged detail section taken as indicated by line 12—12 on Fig. 11.

Throughout the drawings the invention is shown in connection with a typical electrical dental oven. In the drawings the numeral 10 designates a base upon which is mounted a resistance box 11, an oven 12 and a control mechanism 13. The control mechanism comprises a controller arm 14 which is pivoted to the base at 15 and engages contacts 16. The controller arm 14 and the contacts 16 are so arranged as to control the resistance in the resistance box 11. By moving controller arm 14 in the direction indicated by the arrow in Fig. 1, resistance will be cut out thereby allowing the oven to become more highly heated.

Mounted on the side of base 10, as shown in Figs. 1 and 5, there is a clock mechanism 17 on which is mounted a dial 18. The mechanism 17 is preferably an ordinary clock mechanism which may be wound by a key 19 set by a screw 20 and regulated by an

arm 21, but however, I do not wish to limit myself to this particular form of mechanism as it is obvious that other mechanisms could be readily adapted to accomplish the same results. The dial 18 is mounted on the clock mechanism by means of a screw 22 which cooperates with spring washer 23. This construction holds the dial 18 firmly on the clock mechanism and causes it to be rotated by said mechanism. The dial 18 is a flat disk and has notches 24 on its periphery. The notches 24 may be spaced at suitable intervals as will hereinafter be described. Pivotedly mounted at 25 on a bracket 26 is a bell-crank 27 comprising arms 28 and 29. The bell-crank 27 is so arranged that the end of arm 28 engages the periphery of dial 18. Pivotedly connected at 30 to the end of arm 29 is a connecting rod 31 which is carried in a bracket 32. The connecting rod 31 connects the arm 29 to a block 33 which is mounted on a portion of control arm 14 as hereinafter described. At the outer end of control arm 14 there is an enlarged portion 34. The enlarged portion 34 and the slot 35 in it, are curved so as to be concentric with pivot 15. The slot 35 being cut in enlarged portion 34 forms a curved portion 36 around which is mounted block 33. On the upper surface of portion 36 are ratchet teeth 37, clearly shown in Fig. 3. The block 33 is made in two parts 37 and 38 which are held together by means of screws 39. The block 33 is constructed in this manner so that it may be mounted around portion 36. Mounted within the block 33 on a pin 40, which is mounted in portion 37 of the block, is a pawl 41. The end of pawl 41 engages ratchet teeth 37 and is held in engagement with said teeth by means of a spring 42 which extends between portion 38 and pawl 41, as shown in Fig. 3. Extending from pawl 41 through block 33 is a pin 41^a on which is a knob 41^b. This projection from the pawl provides means by which the pawl may be disengaged from the ratchet teeth thus making it possible to move control arm 14 freely. The end of connecting rod 31 forms a yoke 44 which fits over the block 33. The yoke 44 is pivotally connected to the block 33 by means of pivot pins 45 which are screw threadedly engaged in block 33. Between the bracket 32 and the arm 29 there is a spring 46 which tends at all times to keep arm 28 in contact with dial 18.

When the clock mechanism 17 causes the dial 18 to rotate in the direction indicated by the arrow in Fig. 1 the arm 28 will drop into a notch 24. This movement of arm 28, which is one arm of the bell crank 27, will cause movement of connecting rod 31 in the direction indicated by the arrow in Fig. 1. When connecting rod 31 is moved it will carry with it block 33, and block 33 will carry with it the control arm 14, due to the

pawl 41 engaging ratchet teeth 37. The mechanism is designed and proportioned so as to cause the movement of arm 14, caused by the falling of arm 28 into a notch 24, to be great enough to move control arm 14 a distance of one contact. As the dial 18 continues to rotate the arm 28 will be gradually pushed out. This movement will cause the connecting rod 31 and the block 33 to be moved back to the position in which they were before the arm 28 had fallen into the notch 24. But this movement will not cause control arm 14 to be moved due to the fact, that pawl 41 will merely slide over ratchet teeth 37. As the dial 18 continues to rotate the arm 28 will come in contact with the various notches 24 and the control arm 14 will thereby be moved across the contacts 16 until it has reached the last one.

When the control arm is in this position the current from lead wires 50 is passing directly to the oven without passing through resistance in box 11. The oven will rise in temperature and the temperature will be registered by hand 51 of pyrometer 52, the lead wires 53 of which enter the oven. Mounted on the pyrometer, as shown in Fig. 10 there is an adjustable arm 54. The arm 54 is carried in a boss 55 on the side of the pyrometer and is adjustable in said boss. The arm 54 is set in the pyrometer so that the hand 51 will engage it. The arm 54 is adjusted in boss 55 until its end 56 is even with the graduation on the pyrometer at which it is desired to turn the oven off. Arm 54 is set in this position by means of a set screw 57. When the pyrometer hand 51 has come in contact with the arm 56 the main switch 58 of the oven is thrown out. Fig. 6 is a diagram of the means for accomplishing this operation. When the hand 51 engages arm 56 the circuit 60, energized by a battery 61, is closed, and relay 62 closes circuit 63 which is in parallel with the rheostat R (the resistance hereinbefore referred to controlled by controller arm 14). The closing of circuit 63 causes electromagnet 64 to be energized. The electromagnet 64 moves the lever 65, which is pivoted at 66 to a bracket 67, in the direction indicated by the arrow in Figs. 2 and 6. This movement of lever 65 disengages it from pin 68 which is mounted on the blade 69 of the main cut out switch S. The blade 69 is pivotally mounted at 70 on a bracket 71 and engages contacts 72. Connected between the end 73 of blade 69 and base 10 there is a spring 74 which tends at all times to hold the switch open, that is, keeps blade 69 out of engagement with contacts 72. As soon as the lever 65 is disengaged from pin 68 blade 69 is disengaged from contacts 72 by the action of spring 74. The throwing open of switch 58 opens the circuit to the oven and thus prevents it from being further heated.

The system of turning off the oven just described, is a typical way in which it may be done and it will be understood that the invention is not limited to this particular arrangement as the oven could be shut off in many different ways. For instance, as shown in Fig. 8, a fuse 90 may be connected in a lead wire 50 and placed in the oven so as to become heated by the oven. The fuses 10 may be made of a metal that will melt at the desired temperature but large enough not to become heated by the electricity passing through it. With this form of the invention, when it is desired to turn the oven off 15 at a certain temperature a fuse that will melt at that temperature may be placed in the oven. When the temperature of the oven has reached this point the fuse will melt and thereby break the circuit. 20 Although this system is very simple it is not as accurate as the system first described and therefore not adapted for delicate work. The number of notches 24 in the periphery 25 of the dial 18 and the spacing of said notches may be determined experimentally, and dials may be made which will give various heat ranges. In Figs. 8 and 9 is shown a form of dial that may be adjusted to produce any desired heat ranges. In this form of dial 30 there are notches 24^a closely spaced around the entire periphery of the dial and between said notches are arms 81 pivotally mounted by means of screws 80. The arms 81 have a 35 curved surface 82 which is of the same curvature as the outer periphery of the dial. As shown in Fig. 9, the arms 81 may be turned to a position in which they close the slots and form an even surface on which the arm 28 may ride or they may be thrown to 40 a position which allows any notch or notches to be open. With this form of construction, the dial being made relatively large and the notches small and close together, it is possible to set the dial so that it will accurately 45 control the process.

In the dial first described, the notches were of such a depth as to cause the movement of control arm 14 from one contact to the next. In the dial shown in Fig. 8 and Fig. 9, each 50 notch 24^a is of such a depth as to cause the arm 28 to fall in just far enough to cause movement of the mechanism sufficient to move control arm 14^a from one contact to the next. But however, the portion 36 of arm 55 14^a has only one ratchet tooth 37^a for each contact point so that the movement of the arm 28 into a notch 24 will be just enough to catch one ratchet tooth. In this form of device in order to assure positive action and 60 to be sure that the pawl has engaged the ratchet tooth, the arms 81 have rounded portions 81^a which, when the arms are turned so as to open the notches, will project beyond the periphery of the dial. When the 65 arm 18 passes over the rounded portion 81

it causes the entire mechanism to be moved back slightly more than the required distance. This makes the engagement of the pawl and ratchet tooth certain.

In Figs. 11 and 12 is a form of the invention which greatly simplifies the construction. In this form of the invention the control arm of the rheostat R is removed and a brush 100 is mounted at 15 in its stead. The brush 100 engages a commutator 102 on 70 the shaft 103 of the clock mechanism 17^a, the brush is kept in contact with the commutator by a spring 100^a. The commutator is not mounted directly on the shaft but is mounted on a fiber bushing 104 which forms 75 an insulator between the commutator and the shaft. Extending from commutator 102 there is an arm 105 on the end of which is mounted a brush 106. The brush 106 engages contacts 107 which are mounted in a 80 circular fiber block 108. Block 108 is mounted on the clock mechanism 17^a. Clock mechanism 17^a may be the same as the clock mechanism 17 which is used in the other form of the invention. The contacts are 85 mounted in the block in such a manner as to be separated from each other and to form notches between adjacent contacts which will cause brush 106 to slide off of one contact directly onto the next. This makes the 90 changing of the brush from one contact to the next very quick. Connected to contacts 107 there are binding posts 110 which extend through slots 110^a in block 108. The contacts are mounted in block 108 as shown 95 100 in Fig. 11. By moving the binding posts in slots 110^a the contacts may be adjusted so as to be in contact with brush 100 any desired length of time. Extending between the binding posts 110 and the contacts 16^a are 105 wires 112.

The mechanism just described completes the circuit between the point 15 and the various contacts 16^a. The contacts 107 and contacts 16^a are connected up (as shown in 110 Fig. 11) so that the rotation of the brush 106 due to the clock mechanism 17^a will cause resistance to be gradually cut out.

The various arrangements and the details of construction hereinabove described are 115 merely typical embodiments of my invention and therefore I do not wish to limit myself to them but wish to reserve to myself any changes or modifications which may appear to those skilled in the art or fall within 120 the scope of the following claims.

Having described a preferred form of my invention, I claim:

1. In combination with an electric oven, means for varying the temperature of said oven, time regulated means for actuating said varying means, and means for automatically disconnecting said oven upon reaching a predetermined temperature. 125

2. In combination with an electric oven, 130

- means for varying the temperature of said oven, said means embodying variable resistance, and time regulated means for actuating said varying means. 40
- 5 3. In combination with an electric oven, means for varying the temperature of said oven, said means embodying variable resistance, and time regulated means for actuating said varying means, said regulating 45
- 10 means embodying mechanically operated connecting means for said resistance. 50
- 15 4. In combination with an electric oven, means for varying the temperature of said oven, said means embodying variable resistance, and time regulated means for actuating said varying means, said regulating 55
- 20 means embodying a mechanically rotated arm adapted to engage contacts, said arm and contacts being in connection with said resistance. 60
- 25 5. In combination with an electric oven, means for varying the temperature of said oven, said means embodying variable resistance, and time regulated means for actuating 65
- 25 said varying means, said regulating means embodying a mechanically rotated arm adapted to engage adjustable contacts, said arm and contacts being in connection with said resistance. 70
- 30 6. In combination with an electric oven, means for varying the temperature of said oven, time regulated means for actuating said varying means, and means for automatically disconnecting said oven upon 75
- 35 reaching a predetermined temperature, said means embodying a pyrometer arranged to 80 actuate a switch. 85
7. In combination with an electrically heated oven, time controlled means for varying the heating current, said means embodying a rheostat with a movable contact arm and time mechanism to move said arm step by step, and temperature controlled means for entirely cutting off such current. 90
8. In combination with an electrically heated oven, time controlled means for varying the heating current, said means embodying a rheostat with a movable contact arm and time mechanism to move said arm step by step, and temperature controlled means for entirely cutting off such current, said means embodying a switch in the main circuit leading to the oven, and pyrometer controlled mechanism for causing said switch to open. 95
9. In combination, units of resistance, a commutator having contacts in connection with said units of resistance, a contact in engagement with said commutator and time controlled means for relatively moving said commutator and said contact. 100
10. In combination with an electric oven, means for varying the temperature of said oven, time regulated means for actuating said varying means, and means for automatically disconnecting said oven upon reading a predetermined temperature, said means comprising a pyrometer in connection with the oven and arranged to have a moving part in an actuating circuit and adapted to 105 cooperate with an adjustable contact. 110
- In witness that I claim the foregoing I have hereunto subscribed my name this 11th day of June, 1919.
- ALFRED L. WILKES.
